ANDREW B. GRAHAM, PHOTO-LITHO, WASHINGTON, D.C.

UNITED STATES PATENT OFFICE.

STONEWALL J. CONKWRIGHT, OF WINCHESTER, KENTUCKY.

INVALID-BED.

SPECIFICATION forming part of Letters Patent No. 554,580, dated February 11, 1896.

Application filed April 4, 1895. Renewed January 8, 1896. Serial No. 574,757. (No model.)

To all whom it may concern:

Be it known that I, STONEWALL J. CONKWRIGHT, a citizen of the United States, residing at Winchester, in the county of Clark and 5 State of Kentucky, have invented new and useful Improvements in Invalid-Beds, of which the following is a specification.

My invention relates to an improved invalid-bed, and has for its object to provide 10 means for changing the patient from one side of the bed to the other without injury or inconvenience to the patient; to provide a removable cot-section and a removable chair-section by means of which the patient may 15 be removed from the bed to another room or portion of the room in either a recumbent or reclining position; to provide improved means for permitting the patient to evacuate the bowels or bladder without removing from 20 either of the bed-sections, and to improve the construction of this class of beds generally.

To these ends my invention consists in the novel features and in the construction and arrangement of parts hereinafter described, 25 due reference being had to the accompanying drawings, forming a part of this specification, wherein—

Figure 1 is a top plan view of my improved bed-frame, the mattresses being removed. 30 Fig. 2 is an elevation of one side thereof. Fig. 3 is an end elevation. Fig. 4 is a vertical longitudinal section of the chair-section of the bed. Fig. 5 is an end elevation illustrating one of the sections raised into position for shifting the patient from one side of the bed to the other. Fig. 6 is a transverse section taken on the line 6-6 of Fig. 1. Fig. 7 is a bottom plan view of the mechanism for supporting the sections in their elevated positions. Fig. 8 is a detail perspective view of one of the supports. Figs. 9 and 10 are similar views of the brackets and pivot-bolts for pivotally connecting the swinging levers to the bed-sections. Fig. 11 is a similar view of 45 the hinge-joint of one of the sections and the means for locking the same. Fig. 12 is a similar view of the mattresses detached. Fig. 13 is a similar view of the mattress-protector. Fig. 14 is a side elevation of the chair-section 50 removed from the bed and adjusted to position for use as a reclining-chair. Fig. 15 is a

rear elevation thereof. Fig. 16 is a detail sectional view of the means for yieldingly supporting the wire bed-bottom of the middle and foot sections of the chair-section. Fig. 55 17 is a side elevation of the same. Fig. 18 is 18 a perspective view of the adjustable bracket for holding the vessel.

Referring to the drawings, the numerals 1 and 2 indicate the side rails and 3 and 4, respectively, the head and foot rails of the main or bed frame, and which is adapted to be supported upon a bedstead of ordinary or usual construction. Supported upon the said rails are two removable and adjustable bed-sections 6 and 7, which are connected to the head and foot rails as follows:

Pivotedly secured to the center and inner side of the head and foot rails respectively are two levers 8 and 9, a single pivot-bolt 10 serving to connect each pair of levers to the adjacent rails. The other ends of said levers are detachably connected to brackets 11 secured to the inner sides of the ends of the frames of the bed-sections 6 and 7. Said brackets 11, which are more clearly shown in Fig. 9, are preferably each cast in a single piece comprising a base-plate 12 adapted to be secured to the frame of the sections by screws or other suitable fastenings, and bracket-arms 80 13 14 which lie parallel with the base-plate 12, said arms 13 14 being provided with apertures 15, in which is disposed a sliding bolt 16, which is adapted to project into an aperture 17 formed in the base-plate 12, and in which 85 aperture said bolt is normally held by a coiled spring 18 which surrounds it and is confined between the arm 13 and a lug 19 on said bolt. The free end of the bolt 16 is bent at a right angle to the bolt, as at 20, and when the latter 90 is retracted against the tension of the spring 18 by turning the bolt axially the bent or hooked portion 20 engages a shoulder 21 formed on the end of a lug 22 which is cast integrally with the bracket, and is thus held 95 in its retracted position. The outer end of each of the levers 8 and 9 is suitably apertured and rests between the base 12 and arm 14 of its bracket 11, and is pivotally secured thereto by the bolt 16 which passes through 100 said apertured end. It will thus be seen that the bed-sections 6 and 7 are pivotally secured

to swinging levers 8 and 9, which in turn are pivotally secured to the main frame of the bedstead.

To the ends of the frames of the bed-sections 6 and 7 are screwed or otherwise suitably secured brackets 23, each consisting of a base-plate 24, having cast integrally therewith and upon the opposite sides thereof boxes 25 and 26, said boxes being provided with apertures 27 that are in alignment, and in which is disposed a bolt 28 that is held projected through all of said apertures by a coiled spring 29. The free end of the bolt 28 is provided with a bent or hooked portion 30, which, when the bolt is retracted against the tension of the spring 29 and turned axially, bears against the shouldered end of a projecting lug 31 and is thus held in its retracted position. The base 24 of the brackets 23 is screwed to the under side of the end rails of the bed-sections, the boxes 25 and 26 lying upon the opposite sides of said rails, and the said rails are apertured to permit the passage therethrough of the bolts 28.

The adjacent ends of the bed-sections 6 and 7 are pivotally secured together by links 32, each end of which is provided with a longitudinal slot 33, and the opposite slotted ends of said levers are disposed within the boxes 25 of the brackets 23 and pivotally secured therein by the spring-bolts 28. Communicating with each of the slots 33 is a series of inclined recesses 34, and pivotally secured to the opposite ends of each of said links adjacent to the slot 33 is a latch 35, for the purpose hereinafter described. It will thus be seen that the bed-sections 6 and 7 are connected to the main frame of the bed by the swinging levers 8 and 9, and are pivotally connected to each other by the links 32. By lifting either of said bed-sections it will be both raised vertically and swung to one side laterally upon said swinging levers and links, in the manner and for the purpose hereinafter described, and when in its raised position is supported by the following mechanism: To the side rails 1 and 2 of the main frame of the bed is secured a center rail 36, to the opposite sides of which and midway between its ends are pivotally secured levers 37 and 38, the opposite ends of which are pivotally secured to brackets 11, similar to the brackets 23 before described, and which brackets are secured to the side rails of the bed-sections 6 and 7. The ends of the levers 37 and 38 that are pivoted to the center rail, 36, are enlarged, as shown, and upon their adjacent faces are provided with ratchet-teeth 41, arranged in the arc of a circle, as more clearly shown in Fig. 8.

To the under side of the center rail, 36, and midway between the ends of the latter, is pivotally secured by means of a bolt 42, a bar 43, and arranged in bearings in said bar upon each side of its pivoted point are detents 44, (more clearly shown in Fig. 7,) which are normally held in engagement with the

ratchet-teeth 41 of the levers 37 and 38 by coiled springs 45, the said springs permitting the detents to ride idly over the inclined faces 70 of the ratchet-teeth when the levers are swung up to their elevated positions, but causing said detents to engage the vertical faces of said teeth and prevent the levers from swinging down until the bar carrying the detents is oscillated to cause the latter to disengage said ratchet-teeth. In order to facilitate the operation of oscillating said bar, the latter is provided at each end with sliding extensions 46 that are arranged in bearings 47 secured to the under side of the oscillating bar 43, one of said extensions being drawn out when it is desired to operate said bar, as will more fully hereinafter appear, and which may be afterward pushed in under the bed 85 out of the way. The oscillating bar 43 is normally held in position to cause the detents 44 to engage their respective ratchets by means of a bent spring 48, which at its upper end is secured to the center rail, 36, 90 and at its other or free end bears against the oscillating bar 43 and maintains the latter in its normal position.

The bed-sections 6 and 7 consist of rectangular frames 49 approximately of the same 95 length as the main frame of the bedstead and about one-half the width of the latter, and to the side rails of said frames are secured transverse slats 50, upon which rest bed-springs 51, of ordinary construction, and over 100 the latter are stretched wire bed-bottoms 51^a, upon which are supported the mattresses 52 and 53. Said mattresses are approximately of the same size as the frames of the bed-sections 6 and 7, and to one of said mattresses, 105 as 53, are secured straps 54, two of said straps being secured to the upper edge of the mattress near each end and the other straps being secured to the lower edge of the mattress intermediate the first-named straps. The unattached ends of the straps are provided with buttonholes by means of which said straps may be secured to buttons 55 attached to the mattress 52 at points corresponding to the 110 points of attachment of the straps 54 to the 115 mattress 53. Said straps serve to connect the mattresses together to constitute an ordinary single mattress, but when the bed is used as an invalid-bed the mattresses will be disconnected.

Constructed as above described, the operation of my improved bedstead is as follows: If the patient is lying upon one side of the bed, as the bed-section 6, for example, and it is desired to move him to the other side of the 125 bed, the attendant raises the bed-section 6, upon which the patient is lying, said section swinging up upon the levers 8 and links 32, which cause the said bed-section to move laterally over the bed-section 7. As the bed-section 6 is elevated the detent 44 slips idly over the ratchet-teeth 41 on the lever 38 pivotally connected to the bed-section 6, permitting said lever to oscillate upon its pivot.

When the bed-section has been raised to its elevated position said detent engages the vertical face of one of said ratchet-teeth and prevents said lever 38 from swinging down, and thus holds the bed-section in its elevated position. By swinging the pivoted latch 35 at the upper end of the link 32 back from under the pivot-bolt 28 at each end of the bed-section 6 the side of the said section adjacent to the section 7 may then be lowered to incline the bed-section 6 to any extent desired, and may be supported in such position by causing the pivot-bolts 28 to enter either of the inclined recesses 34 that communicate with the elongated slots 33 formed in links 32. The attendant then places his hands under the patient, when by the exercise of but little strength he can transfer the patient to the bed-section 7 and at the same time, the extension 46 on the oscillating bar 43 having first been drawn out, the attendant has only to press his knee against said extension to oscillate said bar and cause the detent 44 to disengage the ratchet-teeth 41 on the lever 37, 25 when the bed-section 6 may be lowered back into place upon the main frame of the bedstead. In order to insure the initial movement of the bed-sections in lowering, I provide each of the said levers 37 and 38 with coiled springs 56, one end of which is connected to said lever and the other end to the center rail, 36, said springs exerting a contractile force to swing the levers down to their lowered positions, as more clearly shown in Fig. 3.

In order that the patient may be removed bodily from the bed to another room or portion of the room, either in a reclining or recumbent position, I make both of the sections 6 and 7 detachable and removable from the bedstead, the one serving as a reclining-chair and the other as a cot.

I will first describe the section 6 adapted to be used as a reclining-chair.

The frame of said section is formed of three jointed sections 57 58 59, the section 57 being the head-section and hinged to the central section, 58, by hinges 60, which permit said head-section to be swung vertically upward, 50 while the foot-section, 59, is in like manner hinged to the central section, 58, by similar hinges 61, that permit said foot-section to be swung vertically downward. The said hinges 60 and 61 each consists of two leaves 62 and 63, the hubs 64 and 65 of which are centrally apertured for the reception of a hinge-pintle, by means of which they are pivotally connected together, and the inner face of one of the hubs, as 64, is formed with a series of ratchet-teeth 66 adapted to be engaged by a detent that projects through an aperture 67 in the hub 65. Said hinges are arranged upon the opposite sides of the frame of the bed-section, and the detents of each pair are operated simultaneously as follows, reference being had to Figs. 1 and 11: Secured to the slats 50, adjacent to the hinges of the head

and foot sections, are bracket-bearings 68, in which are journaled shafts 69, each of said shafts extending from side to side of the bed-section and provided at its opposite ends with detents 70 and 71, which rest within the apertures in the hubs of the hinges, and about said shaft is coiled a spring 72, which at one end bears against the bracket 68 and at its other end bears against a bent portion of the shaft and operates to force the detents into engagement with the ratchet-teeth 66, and thus lock the hinge, and in order that the movement of the shaft in one direction may operate both detents alike one of said detents, as 71, is formed to pass directly through the apertured hub of the adjacent hinge from the inner side, while the other detent, 70, is bent or curved to pass over the side rail of the bed-section and engage the hub of the adjacent hinge from the outer side. The spring 72 operates to maintain both detents in engagement with the ratchet-teeth on the hinge-leaves, and the shaft 69 is provided with a handle 73, by means of which the shaft may be reciprocated in its bearings to retract the detents.

The mattress 52, which rests upon the section 6, is formed in three sections that correspond with the hinged portions of said section 6. To the side rails of the center section, 58, are secured brackets 58^a, which are U-shaped in cross-section and within which are pivoted four legs 74, which are adapted to be folded up under said section, as shown in Fig. 6, and each of said legs has pivotally secured thereto a rung 75, said rungs, when the legs are extended down, overlapping one another, as more clearly shown in Fig. 14, in which position they are secured together by a sliding clasp 76.

From the foregoing description it will be apparent that the section 6 may be removed from the bedstead with the patient lying thereupon, and the head-section 57 may be elevated to any desired inclination, and the foot-section 59 in like manner be lowered, the lock-hinges holding said sections in their adjusted positions. The legs 74 are folded down and the rungs 75 clasped one to the other, as before described, thus forming a chair in which the patient may sit in a reclining position. To the extreme end of the foot-section 59 is hinged a foot-rest 77, which, when not in use, may be folded down beneath the mattress. To permit the foot-section 59 to be lowered it is necessary that the wire bed-bottom 51 be formed in separate pieces, and in order to thus construct said bottom, and at the same time give it a yielding support, I secure to the adjacent ends of the sections 58 and 59 tubular brackets 78, in which are supported uprights 79, provided at their lower ends with screw-threaded extensions 80, which project through the lower apertured ends of said brackets and are provided with stops 81. Arranged between the lower end of each upright 79 and the bottom of the bracket 78 is

a coiled spring 82, and said uprights at their upper ends are provided with eyes in which are journaled rods 83. Each of said rods is formed in two pieces between which the end 5 of the wire bed-bottom is inserted, as more clearly shown in Fig. 16, and the two parts secured together by screws 84. One end of each of said rods is squared to enable it to be engaged and turned by a wrench, and in the 10 upper ends of the uprights 79 are tapped set-screws 85, which serve to hold said rods after they have been rotated to stretch the wire bed-bottom. To the side rails of the section 58 are secured brackets 86, in which are inserted the upright supports 87 of arm-rests 88. From the foregoing description it will be readily understood that the section 6, with the patient thereupon, may be removed from the bedstead and adjusted to form a chair, 20 in which the patient may recline and by means of which he may be moved as desired.

The section 7 is made rigid, and to the side rails thereof, upon their inner sides, are pivoted legs 89, that are adapted to be folded up 25 within the frame of said section and when the latter is removed from the bedstead may be folded down to form supports for said section, which is thus converted into a cot.

It will be understood that in order to 30 move either the chair-section 6 or the cot-section 7 from the bedstead the bolts 16 and 28 must first be retracted, in order to disconnect said sections from the levers 8 and 9 and the links 32. With a view to rendering the 35 operation of lowering the sections 6 and 7 onto the main frame of the bedstead noiseless, I arrange upon the side, head and foot rails of the latter rubber buffers 90.

From the foregoing description it will be 40 readily understood that the patient may be removed from the bed in either a reclining or a recumbent position.

Beneath each of the sections 6 and 7 is arranged an adjustable support for holding a 45 chamber or vessel, which is constructed as follows: To the center rail, 36, of the bedstead is secured a bracket 91, having a plate 92 provided with elongated slots 93, through 50 which pass the fastening screws or bolts that fasten said bracket to the rail. Said bracket is provided with a projecting lug 94, which supports a vertical pin 95, upon which is coiled a spring 96. Arranged in a bearing 97 in the plate 92 is a vertically-adjustable bracket-arm 98, which at its lower 55 end is provided with a laterally-adjustable foot 99 that rests upon the spring 96, coiled about the pin 95, and at its upper end is bent horizontally, as more clearly shown in Fig. 4, to form a support for a laterally-adjustable bracket 100, which has attached thereto a wooden block 101, which serves as a seat for the vessel or chamber; and to said bracket is 60 adjustably secured, by means of a set-screw 102, an expansible annulus 98^a that is adapted to fit around said vessel or chamber, and for that purpose is provided with a slot 103 to

permit of the passage therethrough of the handle of the vessel.

In order that the annulus may fit vessels of 70 different sizes I adjustably secure together its ends by forming a series of keyhole-slots 104 in one of its ends and strike up from its other end a T-shaped catch 105 that is adapted to engage either of said keyhole-slots and 75 thus secure the ends of the annulus together.

The wire bed-bottom and the mattress are suitably apertured to register with the vessel; and within the aperture in the mattress is fitted a plug 106 that is of the shape of a frustum of a cone, and which is held in position 80 by a strap 107, which is secured to the plug permanently and at its opposite ends is fastened to the mattress by button 108.

From the foregoing description it will be 85 seen that the vessel will be held up by the spring 96 close beneath the bed-bottom, and if it is desired to use the vessel while the section is in an elevated position the cross-pins in the pin 95 are shifted so as to raise the spring 90 and cause it to raise the vessel to correspond with the raised position of the bed, and owing to the elongated slots 93 the vessel may be laterally adjusted to properly register with the apertures in the mattress and bed-bottom. 95

In order to prevent the mattress or wire bed-bottom from being soiled I provide a protector 109, consisting of a water-proof annulus 110, having a depending tubular portion 111 that is adapted to be inserted in the aperture 100 formed in the mattress.

It will be understood that each section 6 and 7 is provided with a vessel, as above described, and that both mattresses and bed-sections are apertured to register therewith. 105

By making both of the sections 6 and 7 removable not only can either one of them be removed to serve its own particular purpose, but the sections are made interchangeable, whereby the cot and chair sections may be 110 arranged upon either side of the bed as may prove most convenient and desirable.

Having described my invention, what I claim is—

1. In an invalid-bed, the combination with 115 the bed-frame, of two vertically-adjustable and laterally-movable bed-sections supported upon said frame, substantially as described.

2. In an invalid-bed, the combination with the bed-frame, of two removable, vertically-adjustable, and laterally-movable bed-sections 120 detachably supported upon said frame, substantially as described.

3. In an invalid-bed, the combination with the bed-frame, of two vertically-adjustable 125 and laterally-movable bed-sections, and means for holding said sections in their adjusted positions, substantially as described.

4. In an invalid-bed, the combination with the bed-frame, of two independent vertically-adjustable and removable bed-sections 130 detachably connected to each other and to the bed, substantially as described.

5. In an invalid-bed, the combination with

the bed-frame, of two independent vertically-adjustable bed-sections, means for simultaneously raising and shifting said sections laterally, and means for supporting them in their 5 raised positions, substantially as described.

6. In an invalid-bed, the combination with the bed-frame, of two independent vertically-adjustable bed-sections, means for simultaneously raising and shifting said sections laterally, means for inclining said sections, and means for holding said sections in their adjusted position, substantially as described.

7. In an invalid-bed, the combination with the bed-frame, of two vertically-adjustable 15 bed-sections supported thereon, levers pivotally connected to the opposite ends of said sections and to the ends of the bed-frame, and links pivotally connected at their opposite ends to the ends of the bed-sections, substantially 20 as described.

8. In an invalid-bed, the combination with the bed-frame, of two vertically-adjustable bed-sections supported thereon, levers pivotally connected to the opposite ends of said 25 sections and to the ends of the bed-frame, and links adjustably connected at their opposite ends to the ends of the bed-sections, substantially as described.

9. In an invalid-bed, the combination with 30 the bed-frame, of two vertically-adjustable bed-sections supported thereon, levers pivotally connected to the opposite ends of said sections and to the ends of the bed-frame, links adjustably connected at their opposite 35 ends to the ends of the bed-sections, and supports for holding said sections in their adjusted positions, substantially as described.

10. In an invalid-bed, the combination with 40 the bed-frame, of two vertically-adjustable bed-sections supported thereon, levers pivotally connected to the opposite ends of said sections and to the ends of the bed-frame, links 45 provided at their opposite ends with elongated slots 33 and having a series of inclined recesses communicating with each of said slots, a pivot-bolt 28 arranged at each end of said sections and engaging said slotted links, a latch 35 pivoted to said links and adapted to lock the said pivot-bolts in the 50 slotted ends of the links, and supports for holding the sections in their adjusted positions, substantially as described.

11. In an invalid-bed, the combination with 55 the bed-frame, of two vertically-adjustable bed-sections supported thereon, levers 38 pivotally connected to the bed-frame and to the bed-sections, ratchets formed on said levers, spring-bolts engaging said ratchets to lock the levers in their adjusted positions, and means 60 for retracting said bolts from engagement with the ratchets, substantially as described.

12. In an invalid-bed, the combination with 65 the bed-frame, of two vertically-adjustable bed-sections supported thereon, levers 38 pivotally connected to the bed-frame and to the bed-sections, ratchets 41 formed on said levers, an oscillating bar 43 pivotally connected

to the bed-frame, and spring-detents 44 arranged in bearings on said bar and normally in engagement with said ratchets for locking 70 the levers in their adjusted positions to support the bed-sections, substantially as described.

13. In an invalid-bed, the combination with the bed-frame, of two vertically-adjustable 75 bed-sections supported thereon, levers 38 pivotally connected to the bed-frame and to the bed-sections, ratchets 41 formed on said levers, an oscillating bar 43 pivotally connected to the bed-frame, spring-detents 44 arranged 80 in bearings on said bar and normally in engagement with said ratchets for locking the levers in their adjusted positions, a spring for holding said oscillating bar in position, and sliding extensions connected to the opposite 85 ends of said oscillating bar, substantially as described.

14. In an invalid-bed, the combination with the bed-frame, of two vertically-adjustable bed-sections supported thereon, levers 38 pivotally connected to the bed-frame and to the bed-sections, ratchets 41 formed on said levers, an oscillating bar 43 pivotally connected to the bed-frame, spring-detents 44 arranged 90 in bearings on said bar and normally in engagement with said ratchets for locking the levers in their adjusted positions, a spring for holding said oscillating bar in position, and springs for lowering said levers when 95 they are released, substantially as described. 100

15. In an invalid-bed, the combination with the bed-frame, of two interchangeable bed-sections, as 6 and 7, both detachably supported on said frame, one of said sections, as 7, being provided with folding legs, whereby 105 said section may be removed from the bed-frame and used as a cot, substantially as described.

16. In an invalid-bed, the combination with the bed-frame, of two removable bed-sections 110 supported thereon, one of said sections, as 7, being provided with folding legs to form a cot, and the other section, as 6, being formed with a folding adjustable head and foot section and folding legs to form a reclining-chair, 115 substantially as described.

17. In an invalid-bed, the combination with the bed-frame, of a removable bed-section, as 6, comprising a central section 58, a folding head and foot section, and folding legs hinged 120 to said central sections, hinges 60 and 61 for adjustably connecting said head and foot sections to the central section, one of the hubs of each hinge being provided with ratchet-teeth 66, and the adjacent hub being apertured, as at 67, for the reception of a detent, a rod 69 extending transversely across the bed-section and provided at its opposite ends with detents projecting in the same direction that are adapted to project through said 125 apertured hubs into engagement with said ratchet-teeth, and a spring for forcing said detents into such engagement, substantially 130 as described.

18. In an invalid-bed, the combination with the bed-frame, of a bed-section supported thereon, and provided with an apertured wire bed-bottom, an apertured mattress adapted 5 to register with said apertured bed-bottom, a plug for closing the aperture in the mattress, and a spring-supported bracket for yieldingly supporting a vessel beneath said apertured bed-bottom and mattress, substantially as described.

19. In an invalid-bed, the combination with the bed-frame and an apertured and vertically-adjustable bed-section supported thereon, of a spring-supported bracket adapted to 15 support a vessel beneath the aperture in said bed-section, and means for adjusting said vessel laterally in both a longitudinal and transverse direction, substantially as described.

20. In an invalid-bed, the combination with 20 the bed-frame and an apertured bed-section supported thereon, of a bracket supported beneath said apertured bed-section and provided with a seat adapted to support a vessel, and a vertically-adjustable expansible annulus arranged above said seat and adapted 25 to embrace different-sized vessels, substantially as described.

21. In an invalid-bed, the combination with the bed-frame and an apertured bed-section 30 supported thereon, of a bracket supported beneath said apertured bed-section and provided with a seat adapted to support a vessel, and an expansible annulus arranged above 35 said seat and adapted to embrace different-sized vessels, and provided with a slot for the

reception of the handle of the vessel, substantially as described.

22. In an invalid-bed, the combination with the bed-frame, of two vertically-adjustable bed-sections removably supported thereon, 40 levers detachably pivoted to the opposite ends of said sections and to the ends of the bed-frame, links detachably pivoted at their opposite ends to the ends of the bed-sections, and supports detachably connected to said sections for holding the latter in their adjusted positions, substantially as described. 45

23. The combination with a folding bed-section comprising two or more sections hinged together and one of the end sections being 50 adapted to be folded down to form a foot-section, of wire bed-bottoms rigidly connected to the head and foot of said folding bed-section, tubular bearings 78 secured to the adjacent ends of the foot-section and the adjoining section, coiled springs 82 arranged in said bearings, vertically - movable standards 79 supported upon said springs in said bearings, rotatable cross-bars journaled in said standards and to which the meeting ends of the 60 wire bed-bottoms are attached, and means for holding said bars against rotation, substantially as described.

In testimony whereof I have hereunto set my hand and affixed my seal in presence of 65 two subscribing witnesses.

STONEWALL J. CONKWRIGHT. [L. S.]
